HAIR NET

Ruthard Dietze, Helmstedt, Germany, assignor to Solida
Textil- und Netzwaren-Manufaktur Ruthard Dietze
K.G., Helmstedt, Germany

Filed Mar. 22, 1960, Ser. No. 59,922

Claims priority, application Germany Sept. 22, 1959

Term of patent 14 years

(Cl. D3—13)

FIG. 1

FIG. 2

FIG. 1 is a perspective view of a hair net showing my new design;

FIG. 2 is a side view thereof; and

FIG. 3 is a front view.

The essential features of the design reside in the portion shown in full lines in the drawing.

I claim:

The ornamental design for a hair net, as shown and described.
